his Attorney

UNITED STATES PATENT OFFICE.

GEORGE B. MAEGLY, OF HOUSTON, TEXAS.

PUMP.

Application filed January 31, 1922. Serial No. 532,965.

To all whom it may concern:

Be it known that I, GEORGE B. MAEGLY, a citizen of the United States, residing at Houston, Harris County, Texas, have invented a certain new and useful Improvement in Pumps, of which the following is a full, clear, and exact description, such as will enable others skilled in the art to which it appertains to make and use the same.

10 My invention relates to pumps and has special application to pumps of the reciprocating type for use in pumping fluid from oil or water wells and is designed to meet a very pressing necessity.

15 In ordinary practice sand and other foreign substances accumulate in and around the strainer or filtering device at the lower end of the well, and this sand clogs and obstructs the same to such an extent that it 20 becomes impossible for any oil or liquid to reach the pump. Under these conditions, it becomes necessary to suspend the pumping operation and to remove the pump and tubing and to "wash" the well. This operation 25 not only occasions the loss of much time and production, but is very expensive; in some cases costing from \$300 to \$400. In extremely bad sand conditions this washing operation must be repeated as often as 30 twice each week.

An item of great expense in the pumping of an oil well is occasioned by the wear, and the consequent necessity for replacement, of the cup-leather piston packing of the 35 pump. This wear is caused by sand settling in and around the cups and working down and between the barrel of the pump and the cups. As far as I am informed, no satisfactory method has been devised for washing 40 or cleaning this sand away without pulling the piston from the well. As a result, and under the reciprocating movement of the piston, the sand rapidly cuts and ruins the cups, thus requiring frequent pulling of the 45 piston and installing new packing, which occasions not only loss of time in operation and consequently decreased production, but also increased expense of operation and cost of new cup equipment. This, in the major- 50 ity of smaller wells, makes the difference between operating at a profit and operating at an actual loss.

In most of the smaller wells and in the case of some of the larger ones, the loss of 55 time and expense incident to fighting sand amounts to more than the total value of the

oil produced. As a result, thousands of oil wells which would be otherwise productive are either temporarily shut down or permanently abandoned and junked with great 60 economic loss to the industry. Therefore, some cheap and satisfactory method of meeting and eliminating these troubles is greatly desired, and to this end the principal object of my invention is to provide simple, positive and inexpensive means for washing a sanded well without having to pull the pump and tubing from the well.

A further object is to provide means for 70 dislodging any sand that may clog and obstruct the interstices or openings in the screen or strainer.

Another object is to provide means for 75 projecting water under high pressure into and outwardly through the openings of the strainer in order to loosen and dislodge any sand that may have packed outside the screen, and thus by agitation make the sand mobile and enable the pump to bring any sand or silt within the strainer, and to evacuate same with the regular operation of the pump.

A further object is to provide means not 80 only for removing any obstruction from and cleaning the strainer, but to keep it clean by 85 the actual physical removal of the sand and to create a cavity outside the strainer into which a greater volume of oil can settle and accumulate, and thus be made available for increased production by the pump.

A still further object is to provide simple 90 and positive means for washing any accumulated sand from the leather packing cups ordinarily used on the piston, and thus not only prolong the life of the piston but also 95 increase the working efficiency of the pump.

Referring to the drawings herewith, wherein like numerals of reference are applied to like parts throughout the several views, Figure 1 is a central longitudinal section through a pump barrel equipped with my improvement. Fig. 2 is a similar view showing some of the parts in a different position. Fig. 3 is a transverse section on the line 3—3 of Fig. 1. Fig. 4 is a transverse section on the line 4—4 of Fig. 1.

In the drawing I have shown my improvement as applied to a pump equipped with a working barrel 1, the lower end of which is threaded for attachment by means of a coupling 2 to a strainer 3. The strainer 3 is intended to represent any ordinary type

of strainer, and I have shown for this purpose the usual perforated pipe commonly employed. The lower end of the strainer is shown as equipped with a perforated cap 5 to protect the same in operation.

At the lower end of the working barrel 1, I have fixed a foot valve comprising a downwardly extending sleeve or tube 5, the upper end of which is extended laterally to form 10 an annular flange 6 to be clamped within the coupling 2 and between the adjacent ends of the working barrel and strainer respectively. The upper end is closed except for a central valve passage 7 formed into 15 a seat for an ordinary type of upwardly opening ball valve 8.

The upper end of the working barrel 1 is threaded for some distance downwardly to provide attachment for a coupling 9. 20 This coupling extends outwardly and upwardly and is threaded at 10 for attachment to a short length of pipe 11 secured at its upper end to a similar coupling 12 by means of which it is joined to the lower end of 25 the tubing 13. The working barrel is extended upwardly within the chamber 14 formed within the pipe 11 to a point spaced somewhat from the lower end of the tubing 13 as shown in the drawing. The working 30 barrel within this chamber is perforated toward the lower end of said chamber at 15 to provide a fluid passage, the purpose of which will be later explained.

Within the working barrel 1 a plunger of 35 the ordinary reciprocating type is adapted to operate. The plunger which I prefer to use comprises a lower tubular portion or head 16, threaded exteriorly at its lower end for attachment to a cap 17. This cap extends downwardly a slight distance below the end of the plunger and has a cross supporting member 18 shown particularly in Fig. 3. This cross piece is perforated centrally and threaded for attachment with a downwardly projecting pin 19. The said pin 19 is slightly longer than is the working 45 stroke of the piston and has at its lower end an enlarged head 20.

At the upper end of the head 16 of the plunger the diameter of the tube is enlarged at 21 to provide a valve chamber at the lower end of which the fluid passage is formed into a valve seat 22 to accommodate the ball valve 23. At the upper end of the chamber is a cross pin 24 to limit the upward movement of the valve. The upper end of the valve chamber is adapted for connection with a sucker rod. In Fig. 1 I have shown this chamber threaded interiorly for connection with a hollow sucker rod 25. It is obvious however, that the usual solid sucker rod may be used, and in Fig. 2 I have shown the upper end of the valve chamber connected by means of a plug or coupling 26 to a solid sucker rod 25'. When

this sort of sucker rod is used the valve chamber 21 is perforated above the pin 24 at 27, to furnish an outlet for the fluid being pumped.

In order to adapt my device for the occasional cleaning and flushing of the well screen and strainer while the piston is still in the well, I have devised means for opening the valve passages past the plunger and standing valve. At the lower end of the 70 pump barrel I contemplate raising the standing valve 8 from its seat. To accomplish this I use a ball grappling device comprising a short length of pipe 28 of such size as to fit loosely inside the working barrel. 75 This pipe is threaded at its upper end for connection with a cap 29, said cap being provided with a central opening 30 therein, to allow a loose sliding connection with the pin 19 on the plunger. The opening 30 is somewhat larger than the said pin and will thus allow the free passage of fluid outside and around the said pin. The head 20 of said pin is of such diameter as to extend beyond the said opening as shown particularly 80 in the drawing. The lower end of the pipe 28 is slotted in such manner as to provide four downwardly extending arms 31, these arms being curved inwardly at the lower end so as to fit beneath the lower surface of the ball valve 8. When thus resting on the upper surface of the valve plate 5, the tube 28 does not contact in any way with the valve, but when the tube is raised upwardly 85 the curved lower ends thereof will contact with the sides of the valve and raise the valve from its seat in an obvious manner.

Within the lower portion of the standing valve 5 I have secured a downwardly extending imperforate pipe 32. This pipe projects downwardly to a point spaced somewhat from the lower end of the strainer and serves as a means for more efficient handling of sand which may find entrance to the strainer; thus, sand entering through the foraminations in the strainer will fall downwardly toward the lower end thereof and around the mouth of the pipe 32. The suction of the pump will be thus enabled to draw the sand within the fluid strainer upwardly past the standing valve 8 and the working valve 23 toward the surface.

In the operation of my device the reciprocation of the sucker rod will cause the plunger to move back and forth between the upper end of the tube or pipe 28 and the position shown in Fig. 1. While the plunger is thus reciprocating, the pin 19 will also work back and forth between the position shown in Fig. 1 and a position slightly above the foot valve, and in this operation, the said pin will have no function. The working of the piston will draw the fluid inwardly through the strainer and upwardly through the suction pipe 32 and into the 120 125 130

working barrel in the usual manner. The forming of the suction opening in the pipe 32 toward the lower end of the strainer will serve to keep the sand moving and draw 5 it upwardly during the pumping operation, to the surface.

When it is found that the oil is not entering the strainer properly due to clogging of the screen and strainer with sand, it 10 becomes necessary to clean away the sand clogging the openings therein. The plunger is then raised to a position shown in Fig. 2 by hoisting on the sucker rod attached thereto. In that position the upper 15 end of the packing cups 33 on the outer surface of the plunger will be raised to a point closely adjacent the upper end of the working barrel. The lower cups 33 will then be slightly above the openings 15 in the working 20 barrel. In this position any fluid which may be within the working barrel above the plunger may pass outwardly through the space 34 at the upper end of the working barrel into the chamber 14 and from thence 25 through the openings 15 in the working barrel below the plunger. The fluid will then find a passage past the standing valve 8 which has been raised from its seat by the member 28 and under gravity pressure will 30 then pass outwardly through the strainer and the screen. The head of fluid that may be standing in the tubing will ordinarily be sufficient to flush the screen. It will be obvious however, that liquid may be pumped 35 from the surface to supply any deficiency of liquid in the tubing necessary to accomplish this purpose.

I also contemplate the reciprocation of the plunger from the position shown in 40 Fig. 2 and when the plunger is operated in this position, it will cause a surge or intermittent flow of fluid downwardly into the screen and outwardly through the openings therein and backwardly again into the screen 45 and up into the working barrel. By thus agitating the fluid in the lower end of the well the sand may be loosened and mixed with the fluid to such an extent that the ordinary operation of the pump plunger thereafter will raise the fluid and sand 50 upwardly to the surface. If this operation is continued a settling cavity for oil will be formed outside the screen, thus increasing the production of the well.

55 When the screen has been properly cleaned, the plunger may be lowered to its ordinary position shown in Fig. 1 and the pumping operation may again proceed. It will thus be obvious that the strainer or 60 screen may be cleaned at any time when it is found desirable, without the withdrawal of the piston or tubing from the well, and in fact, the piston itself may be employed to facilitate this operation. The producer is 65 thereby enabled to keep his pump operating

continuously through long periods without the usual loss of time and labor necessitated by the withdrawal of the piston from the well. Furthermore, it will be apparent that when the fluid is pumped downwardly from 70 the surface to clean the strainer, it will also serve to wash away any sand adhering about the plunger or the cups thereon, and tending to clog its operation. By thus removing the sand from about the plunger, the usual 75 wear due to the presence of the sand, will be greatly reduced and the plunger will be thereby enabled to operate for much longer periods of time without the necessity of replacing the cups thereon. 80

The further advantages of my improvement will be apparent to one skilled in the art without further description.

What I claim as new and desire to protect by Letters Patent is:

1. In a device of the character described, the combination with a pump for removing liquid from a well, of a sand screen for said pump, a pump barrel above said screen and means for flushing said screen through said 90 pump barrel from above without removing said pump from the well.

2. In a pump for deep wells, the combination with a sand screen, of a pump barrel, a piston therein and means for forcing liquid downwardly through said pump barrel past said piston to wash said screen without removing the piston and pump barrel 95 from the well.

3. In a device of the character described, the combination with a reciprocating piston, a pump having a supply of liquid above the same, of a sand screen for said pump, and means for forcing said liquid downwardly 100 through the barrel of said pump to flush and clean said screen.

4. In a device of the character described, the combination with a pump, a piston and a sand screen for said pump having a supply of liquid therein below said pump, and means including said piston for utilizing 105 said liquid to scour and clean said screen without moving the pump from the well.

5. In a device of the character described, the combination with a sand screen, of a pump having a plurality of valves and means adapted for forcing liquid downwardly thru said pump past said valves to wash and clean said screen. 115

6. In a device of the character described the combination of a pump barrel, a well screen at the lower end thereof, a piston in said pump barrel above said well screen and means including said pump barrel to wash 120 said screen free of sand without removing said pump piston from said pump barrel.

7. In a pump having a reciprocating piston, the combination of a foot valve, a screen and means for simultaneously moving the piston and unseating said valve to clean the 125 130

said valve and screen without removing same from the well.

8. In a pump, the combination with a pump barrel, a piston therein having a channel to permit fluid to pass therethrough, of means operable when the piston is raised above its normal operative position for establishing a second channel to enable fluid to pass around said piston and downwardly through said pump barrel.

9. In a device of the character described, the combination with a string of pipe having a screen thereon, of means comprising a pump barrel and piston therein adapted to force liquid upwardly through said pipe and means for by-passing and forcing liquid at times around said piston and downwardly through said pipe and pump barrel, to said screen, to flush the same.

10. The combination with a pipe for conveying liquid, of a pump comprising a working barrel and a piston adapted for forcing liquid upwardly through said pipe, a perforated tubular extension on said barrel adapted for receiving said piston at times to permit liquid to pass through said pipe in the opposite direction.

11. In a pump for deep wells, a working barrel, a standing valve connected therewith, a strainer below said valve and a piston in said working barrel, in combination with a liquid by-pass above the normal working position of said piston, and means connecting said piston and standing valve whereby the raising of said piston to the level of said

by-pass will raise said valve and permit a passage of liquid downwardly past said piston and valve to said screen.

12. In a pump for deep wells, a working barrel, a standing valve, a strainer, and a piston in said working barrel, in combination with a liquid by-pass above the normal working position of said piston, a valve lifting means enclosing said foot valve and a pin connecting said piston and valve lifting means whereby the raising of said piston to a point adjacent said by-pass will unseat said foot valve.

13. In a pump, a string of tubing, a working barrel, a piston reciprocable therein, and a coupling of larger diameter than said working barrel connected to said working barrel at a point below the upper end thereof and serving to space the tubing and working barrel slightly apart, the working barrel being perforated inside said coupling, for the purpose described.

14. The combination with a pipe for conveying liquid, of a working barrel and a piston adapted for forcing liquid through said pipe in one direction, a tubular extension on said barrel adapted for receiving said piston at times, means for lifting the piston into said extension and means for then bypassing liquid around said piston and through said pipe in the opposite direction.

In testimony whereof, I hereunto affix my signature, this the 28th day of January, A. D. 1922.

GEORGE B. MAEGLY.
